UNITED STATES PATENT OFFICE.

PATRICK D. SKAHEN, OF SYRACUSE, NEW YORK.

ROUGH BOX FOR BURIAL-CASKETS.

SPECIFICATION forming part of Letters Patent No. 734,196, dated July 21, 1903.

Application filed October 10, 1902. Serial No. 126,691. (No model.)

To all whom it may concern:

Be it known that I, PATRICK D. SKAHEN, a

citizen of the United States, and a resident of

Syracuse, in the county of Onondaga, in the
5 State of New York, have invented new and
useful Improvements in Rough Boxes for
Burial-Caskets, of which the following, taken
in connection with the accompanying draw-
ings, is a full, clear, and exact description.10 This invention relates to rough boxes for
inclosing burial-caskets, and is designed more
particularly for the species of rough boxes
which are formed of sheet iron or steel.15 The object of my present invention is to
muffle or deaden the sound incident to the
dropping of the grave-closing material onto
the lid of the rough box in the operation of
burying the rough box; and to that end the
invention consists in the novel construction
20 and combination of parts hereinafter de-
scribed and claimed.In the annexed drawings, Figure 1 is a side
view of a rough box embodying my improve-
ments, and Fig. 2 is an enlarged transverse
25 section on line X X in Fig. 1.A represents the body of the rough box,
which is formed of suitable sheet metal and
with its walls continuous from the bottom to
the top of the box. The tops of these walls
30 are formed with outwardly-projecting flanges
a a, as shown in Fig. 2 of the drawings. C
denotes the lid of said box, which lid is also
formed of sheet-metal, preferably boiler iron
or steel, and is made large enough to overlap
35 the flanges a. The edges of said lid are bent
down to form depending flanges b, which abut
against the edges of the flanges a, and thus
prevent lateral movement of the lid when
seated upon the box.40 c represents a gasket or suitable packing
interposed between the flanges a and over-
ing margins of the lid.The aforesaid construction of the body of
the rough box and its lid is similar to that
45 shown in my Patent No. 709,423, dated Sep-
tember 16, 1902. There is, however, some
objection to the use of metallic rough boxes,
especially when the metallic walls thereof ex-
50 tend from the bottom continuous to the top
of the box, owing to the disagreeable sound
incident to the vibrations of the lid and wallsof the box produced by the dropping of earth
onto the metallic lid in the operation of clos-
ing the grave. To overcome this objection,
I provide the said lid with suitable means for
55 muffling or deadening the aforesaid sound,
for which purpose I prefer a board d, of suit-
able wood or other fibrous material, which
board I fasten to the under side of the lid by
means of bolts e e or rivets or other suitable
60 means. Aside from the aforesaid muffling
effect the board d when securely bolted to the
lid also serves to brace the lid to prevent its
springing and buckling, and by making the
board of proper length and width to abut
65 with its edges against the inner sides of the
box the top portion of the box becomes braced
to prevent inward deflection thereof, and at
the same time the gasket c is retained on its
seat between the flanges b of the lid and edges
70 of the board.The box A is provided with suitable han-
dles i, by which to carry the box. The lid C
is also provided with handles j, suitably
shaped to afford convenient means for lifting
75 the lid from the box when desired.To provide convenient and efficient means
for fastening the lid to the body A without
piercing and injuring the gasket c, I employ
cam-levers f, which are pivotally connected
80 to brackets g, attached to the metallic lid C
and formed with depending portions extend-
ing beneath the lid-flanges b and terminating
in ears, to which the levers f are pivoted, as
shown at h. Said levers are shaped so that
85 when they are in position for locking the lid
C on the body A the main portion or manipu-
lative ends of said levers bear on the side
of the box A, while the cam portions l bear
90 on the under side of the flanges a and adja-
cent portions of the side of the box or body
A, which serves to retain the levers in their
locking position.In removing the lid from the box the depend-
ing portions of the brackets yield sufficiently
95 outward to the necessary force applied to the
levers to throw them out of their aforesaid
engagement.

What I claim as my invention is—

1. A casket-inclosing box having the lid
100 formed of metal, and a muffling-board of non-
metallic material secured to and covering the

under side of said lid and extending to the inner sides of the walls of the box as set forth and shown.

2. A casket-inclosing box formed of metal and with outwardly-projecting flanges around its top, the lid formed of metal overlapping said flanges, and formed with depending flanges engaging the edges of said outwardly-projecting flanges, a packing interposed be-

tween the lid and flanges of the box, and a non-metallic muffling-board secured to the under side of the lid and extending to the inner sides of the walls of the box as set forth and shown.

PATRICK D. SKAHEN. [L. S.]
